THREAD CUTTING MECHANISM FOR
BOX LOOMSWilliam J. Ingham and Joseph Larouche,
Nashua, N. H.

Application June 16, 1931, Serial No. 544,722

18 Claims. (Cl. 139—116)

In weaving pattern fabrics in box looms the changing of the shuttles required to produce the desired pattern results in the formation of loose loops of filling attached to the selvage of the fabric at the drop box side of the loom. These loops are caused by the fact that when any shuttle is moved into an idle position by the raising or lowering of the box, a strand of filling is left running from the fell of the goods to the bobbin in the shuttle which has just been retired, and when this shuttle is again brought back into working position and makes its first pick, it will loop the filling around the entire width of fabric which has been woven in the meantime.

In our Patent No. 1,892,020, granted April 21, 1931, we have shown and described a mechanism for preventing the formation of these loops and for automatically cutting off, at a point close to the selvage, any strand of filling running from the selvage to an idle shuttle. This mechanism has proved very satisfactory in practice. It operates while the weaving operation progresses, and consequently avoids any necessity for a subsequent hand trimming. So far as we are aware, it is the only mechanism for performing this function which has proved commercially successful.

The present invention relates to mechanisms of the general type above described. It aims further to perfect and improve mechanisms of this general character, and more especially the mechanism shown in our prior patent, with a view to increasing the life and reliability of such mechanisms, simplifying their construction, and facilitating their installation on looms already in use. The nature of the invention will be readily understood from the following description when read in connection with the accompanying drawings, and the novel features will be particularly pointed out in the appended claims.

In the drawings,

Figure 1 is a perspective view of those parts of a box loom with which the mechanism provided by this invention is more particularly associated;

Fig. 2 is a side view on a larger scale of the mechanism shown in Fig. 1 for cutting the filling;

Fig. 3 is an exploded perspective view of parts of the mechanism shown in Fig. 2;

Fig. 4 is a perspective view of the thread clamping device and a part of the operating means therefor;

Fig. 5 is a front view of the thread clamp shown in Fig. 4; and

Fig. 6 is a side view, partly in cross section, of the parts shown in Figs. 4 and 5.

Referring first to Fig. 1, the drop box of the loom is indicated at 2, the lay at 3, the lay sword at 4, and the reed at 5, these parts being constructed, arranged and operated in the usual manner.

The thread cutting mechanism provided by this invention resembles that shown in our patent above designated in that it includes means for gripping the filling thread running from the selvage of the goods to a bobbin in an idle shuttle, and means for severing the thread so gripped at a point close to the selvage of the fabric. The present invention, however, has simplified the operating mechanism for the thread gripping means, has improved the cutter, and has placed both of these devices under the control of the pattern mechanism of the machine so that either or both of them can be operated only during those periods when such operation is necessary or desirable.

It is desirable to mount the thread clamping or gripping device for movement to follow the swing of the filling to be grasped, at least during the periods in which the clamping device is to be operated, and this is most conveniently accomplished by supporting the gripping device directly on the lay as in the construction shown in our prior patent. Referring more particularly to Figs. 1 and 4, it will be seen that the usual shuttle box mouth piece has been replaced by a special mouth piece or a bracket 6 which is bolted to the lay. This bracket has a lower surface 7 lying above the path of the shuttle and a vertical side piece 9 which is positioned at the forward side of the shuttle race 8, these parts defining the top and one side of the mouth of the shuttle box.

The thread gripping device is mounted on the bracket 6 and comprises a roughened plate 10 which is secured to the forward surface of the upright part 9, and a cooperating U-shaped member 12 which embraces a vertical leg 13 of a casting or cover 14 and is guided on pins 15—15 for movement toward and from the plate 10. Springs 16—16, Fig. 6, which are coiled around the pins 15—15 tend to hold the member 12 in contact with the plate 10. A blade 17 is mounted to swing between the two parts 10 and 12, this blade being removably secured to a head 18 which is supported on a rock shaft 20 to rotate therewith, the rock shaft, in turn, being supported in the bracket 6. The head 18 includes a toothed section 21 meshing with gear teeth 22 on the larger end of an operating arm 23 which is pivoted on the bracket 6 at 24 and extends rearwardly so that it swings in a plane at approximately right angles

to the plane of movement of the blade 17. A coiled spring 25, Fig. 1, tends to lift this arm and to hold it normally in the position shown in Figs. 4 and 5 where it maintains the blade 17 in its elevated position, as shown in said figures.

When the pattern mechanism calls for a change in color of the filling, and therefore for a change in shuttles, the drop box 2 is raised or lowered, thus moving the working shuttle into an idle position and bringing another shuttle into working position. Upon the next beat-up of the lay, a strand of filling F, Figs. 1 and 4, will be left running from the fell of the goods to the shuttle which has just been retired from operation. As the lay swings backward again a roll 26 on the end of the arm 23 will strike a normally stationary cam 27, Fig. 1, and swing the rearward end of the arm 23 downwardly, thus operating the blade 17 of the clamping device and causing it to force a bight of the strand F between the clamping members 10 and 12, as shown in Fig. 4. Immediately after this operation has occurred, the blade 17 is swung into its open position again by the spring 25, but the bight of filling which it has just forced between the parts 10 and 12 is held securely gripped by them. The gripping device thus may be considered to include three elements, namely, those indicated at 10, 12 and 17. The parts 10 and 12 are operative of and by themselves to grip and hold the yarn. The blade 17, however, serves to force the bight of filling or yarn between the parts 10 and 12 and cooperates with them while it is between them to grip the filling.

Preferably the edge of the part 9 across which the filling is drawn is roughened or ribbed horizontally to prevent the filling from slipping downwardly. It may also be pointed out that the lower end of the extension 9 terminates in a lug or foot 28 which lies approximately flush with the surface of the shuttle race and closes the vertical gap which usually is provided in a box mechanism to permit the strands of filling running to the idle shuttles to drop down below the level of the shuttle race. In other words, this shuttle box mouth is so constructed that the filling running to an idle shuttle will be held within the range of operation of the gripper blade 17.

While the strand of filling running to a shuttle which has just been retired is gripped in the manner above described, it is parted or severed at a point closely adjacent to the selvage of the goods by a cutter of novel construction. Referring to Figs. 1, 2 and 3 it will be seen that this cutter is associated with the temple roll 30. It comprises a stationary blade 31 which is secured between the upper and lower parts 32 and 33, respectively, of a temple frame 34 that is mounted on the breast beam. Cooperating with the stationary cutter is a movable cutter 35 lying immediately beside the stationary cutter 31 and held against the latter by a coiled spring 36 which encircles the temple roll shaft 37, this shaft extending through both the cutters 31 and 35. A stub shaft 38 is secured to the movable cutter 35 and passes through a slot 40, Fig. 2, in a lever 41 which is fulcrumed at 42 on the temple frame 34. A spring 43 coiled about the pivot stud 42 acts on the lever 41, and when permitted to do so will hold this lever forward in the position in which it is shown in Fig. 2. In this position the cutter is open. When the lay strikes the lower end of this lever, however, it forces it forwardly, and this movement of the lever operates through the pin 38 to force the movable cutter 35 for-

wardly, this cutter being provided with a slot 47 through which the temple roll shaft 37 projects. This blade 35 is guided between the lugs 32 and 33 on the temple frame. After the lay has operated the cutter it engages the heel 48 of the temple and forces the whole temple mechanism forwardly in the usual manner, the parts of the cutter moving bodily with the temple.

The cutter operates immediately beside the selvage at the fell of the goods, and in order to facilitate the guiding of the strands to be severed into proper relationship to the cutter, the blade 35 is provided with an extension 44 projecting at right angles to the main body of the blade and designed to extend under and to bear against the warp threads at the fell. In other words, the upper edge of this extension 44 lies substantially in line with the lower edge of the slot in the temple roll casing or guard. Located just behind this extension is a notch 45 in the cutter 35 and a bevelled surface 46 is formed between the upper rearward end of this notch and the upper surface of the extension 44. Consequently, when a shuttle has been retired from action the thread running from this shuttle to the selvage will be caused to ride up over the surface 46 and to drop into the notch 45 due to the takeup movement of the cloth. Immediately after this thread enters the notch 45 it will be severed by the next forward movement or cutting stroke of the movable cutter 35, this stroke serving to carry the front wall of the notch 45 forwardly past the rear edge of the stationary cutter 31 and to shear off the thread between these two members. This hook-shaped blade 35 and the parts associated therewith provide a very reliable cutter construction.

The mechanism above described thus operates very positively and reliably to grasp a strand of filling running to a shuttle which has just been moved into an idle position in the drop box and to sever this strand of filling at a point closely adjacent to the selvage of the goods. After the filling has been so cut, the cut end will drop down in front of the lay but the bight of filling will still be gripped between the parts 10 and 12. Consequently, when the shuttle to which this filling runs is again brought into operation, the end of the filling will still be held while the shuttle makes its first pick. In fact, a bight of filling once forced between the gripping members 10 and 12 is never released until both ends of it have been cut and it is finally forced out from between the parts 10 and 12 at the back of the gripper or clamp due to the action of the blade 17 in forcing additional strands into the gripper.

In weaving some fabrics the shuttle changes are so infrequent that in order to save wear and to increase the life of the mechanism it is desirable to place either the gripping or cutting devices, or both of them, under the control of the pattern mechanism of the machine. The present invention provides a simple and reliable means for accomplishing this object.

Referring to Fig. 1 it will be observed that the relatively stationary cam 27 which cooperates with the arm 23 to operate the gripper blade 17 is integral with a plate 49 that is mounted in a dove tail guideway formed in a plate 50 which is secured rigidly to the frame of the machine, this guideway permitting a horizontal sliding movement of the cam 27 in a direction parallel to the lay. This arrangement permits the shifting of the cam 27 into and out of cooperative relationship to the roll 26 on the arm 23.

In order to produce such a shifting movement

automatically connections are provided running from this cam to the lever 51 which forms a part of the pattern mechanism for controlling the sequence of operations of the loom. Fig. 1 shows 5 a part of a standard multiplier motion of a Crompton & Knowles blanket loom, this multiplier including two lobed cams 52 and 53, respectively, which are rotated selectively and intermittently under the control of the chain 54 of the pattern 10 mechanism. Each of the cams 52 and 53 is arranged to act on a bar 55 which is pivoted to the lever 51, and a spring (not shown) acts through the lever to press its forward end upwardly and thus to hold the bar 55 in contact with one or 15 both of the cams 52 and 53. When this pattern mechanism calls for a change in color, and consequently indicates a shift in the shuttles in the drop box 2, one of the cams 52 or 53 forces the bar 55 downwardly, thus depressing the forward 20 end of the lever 51. This movement is transmitted through a rod or link 56 to an arm 57 secured fast on a horizontal rock shaft 58 which is supported in brackets bolted to the frame of the machine. Another arm 60 secured to the end 25 of this rock shaft has a pin and slot connection 61 with the plate 49 which is integral with or rigidly secured to the cam 27. The downward movement of the lever 51 therefore operates through the connections just described to shift 30 the cam 27 toward the right, Fig. 1, into cooperative relationship to the operating arm 23 for the gripper blade 17. The gripper device thus is brought into action substantially simultaneously with the shifting of the shuttles in the boxes and 35 it remains in operation for a period determined by the action of the pattern mechanism, usually for several picks.

When the lever 51 is again raised it tends to operate through the connections with the cam 27 40 to shift this cam into an inoperative relationship to the arm 23 and this result definitely is accomplished through the joint action of the pattern mechanism and the spring 62 which connects the arm 57 with a stationary part of the frame; these 45 parts serving normally to hold the gripper in an inactive condition.

A part of the connections just described are also utilized to throw the cutter into and out of action simultaneously with the shifting of the 50 cam 27. Referring to Figs. 1 and 2, it will be seen that a latch 63 is pivoted on a stationary part of the temple frame at 64, Fig. 1. The rearward end of this latch includes a hook 65, Fig. 2, which drops over the pin 38 when the 55 cutter is forced into its extreme forward position and thus retains the cutter in the latter position where it is just beyond the range of movement of the lay. In order to release the cutter, a bell crank lever is fulcrumed on a bracket 66, Figs. 1 and 2, secured to the breast beam and includes a horizontal arm 67 adapted to engage a cam-shaped surface 68 formed on the lower side of the latch 63. This bell crank lever also includes an upright arm 70 which is connected by a link 71 with one arm of a bell crank lever 72, Fig. 1, the opposite arm of which is connected by a rod 73 to an arm 74 secured rigidly on the rock shaft 58 previously referred to. Normally the cutter is held in an inactive position by the latch 70 63, but when the lever 51 of the multiplier motion is depressed in the manner above described, this movement is transmitted through the connections just described to the bell crank lever 67-70 and swings the horizontal arm 67 of this lever forward into the position shown in Figs. 1

and 2, where it lifts the latch 63 and causes it to release the cutter. The hook-shaped cutter blade 35 is immediately moved backward by the spring 43 and lever 41, and the cutter continues to operate until the pattern mechanism lifts the arm 51, this movement resulting in allowing the latch 63 to drop again where it will catch and hold the pin 38 on the cutter.

The invention thus provides a mechanism for gripping and cutting the filling running from the selvage of the goods to an idle shuttle in the drop box which is simple in construction, extremely reliable, and which can be manufactured and installed on a loom economically. The gripping and cutting devices may either be run continuously or they can be placed under the control of the pattern mechanism of the machine so that they will be brought into operation and thrown out of action again at predetermined times. In a typical arrangement the gripping and cutting devices are held normally out of action but are brought into operation temporarily when the working shuttle is retired and thrown out of action shortly thereafter. Excessive wear of the parts thus is avoided, and the life of the device is correspondingly increased.

In some cases, as for example in weaving a blanket having a large plain body or central area and a striped margin, the pattern chain of the loom is run continuously during the weaving of the plain section so that the loom will make two picks with one shuttle and then two picks with another shuttle, both shuttles carrying the same color. Under these circumstances it is desirous to hold the gripping and cutting devices

out of action so long as the chain is running, and to bring them into operation only when the chain stops. This may conveniently be accomplished by reversing the connections between the rock shaft 58 and the lever 51 and shifting the point of attachment of the rod or link 56 to the opposite side of the fulcrum of the lever 51 so that the cam 27 will be held out of its operative position so long as the forward end of the lever 51 is depressed and will be brought into its operative position only when the forward end of said lever is allowed to rise.

While we have herein shown and described a preferred embodiment of our invention, it will be understood that the invention may be embodied in other forms without departing from the spirit or scope thereof.

Having thus described our invention, what we desire to claim as new is:

1. In a box loom of the type in which pattern mechanism automatically controls the shifting of the shuttles in the drop box, the combination of means mounted on the lay of the loom for gripping a strand of filling running from the selvage of the fabric in the loom to an idle shuttle in the drop box, mechanism arranged to be operated by the movement of the lay but under the control of the pattern mechanism of the loom for operating said gripping means, and means operable on the strand so gripped to sever it at a point adjacent to the selvage of the goods.

2. In a box loom of the type in which pattern mechanism automatically controls the shifting of the shuttles in the drop box, the combination of means mounted on the lay of the loom for gripping a strand of filling running from the selvage of the fabric in the loom to an idle shuttle in the drop box, mechanism for utilizing the movement of the lay to operate said gripping means, means for normally holding said grip-

ping means in an inactive condition, means for acting on a strand of filling so gripped to sever it at a point adjacent to the selvage of the goods, and connections for causing the pattern mechanism of the loom to bring said gripping means into action at predetermined times in the cycle of operations of the loom.

3. In a box loom of the type in which pattern mechanism automatically controls the shifting of 10 the shuttles in the drop box, the combination of means mounted on the lay of the loom for gripping a strand of filling running from the selvage of the fabric in the loom to an idle shuttle in the drop box, mechanism for utilizing the 15 movement of the lay to operate said gripping means, means for normally holding said gripping means in an inactive condition, means for acting on a strand of filling so gripped to sever it at a point adjacent to the selvage of the goods, 20 and connections for causing the pattern mechanism of the loom to bring said gripping means temporarily into operation upon a call for a change of shuttles at the drop box.

4. In a box loom of the type in which pattern 25 mechanism automatically controls the shifting of the shuttle in the drop box, the combination of means for gripping a strand of filling running from the selvage of the fabric in the loom to an idle shuttle in the drop box, mechanism for utilizing the 30 movement of the lay to operate said gripping means, means arranged to be operated by the lay for severing a strand of filling so gripped at a point adjacent to the selvage of the goods, means for normally holding both said 35 clamping means and said severing means in an inactive condition, and connections for causing the pattern mechanism of the loom to bring both said severing and gripping means into operation temporarily when the pattern mechanism retires 40 a working shuttle at the drop box.

5. In a box loom of the type in which pattern 45 mechanism automatically controls the shifting of the shuttles in the drop box, the combination of means mounted on the lay of the loom for gripping a strand of filling running from the selvage 50 of the fabric in the loom to an idle shuttle in the drop box, mechanism for operating said gripping means including cooperating parts mounted for relative movement into and out of cooperative relationship, means under the control of the pattern 55 mechanism for normally holding one of said parts out of cooperative relationship to the other and thereby maintaining the gripping means in an inactive condition, connections for causing said pattern mechanism to relatively move said parts into cooperating relationship to each other under predetermined conditions, and means for severing the strand so gripped closely adjacent to the selvage of the goods.

6. In a box loom of the type in which pattern 60 mechanism automatically controls the shifting of the shuttles in the drop box, the combination of means for gripping a strand of filling running from the selvage of the fabric in the loom to an 65 idle shuttle in the drop box, mechanism for operating said gripping means comprising a part movable with the lay and a normally stationary member cooperating with said part to operate the latter, means for normally holding said part and 70 said member out of cooperative relationship to each other, and connections for causing the pattern mechanism to effect a relative shifting movement of said parts into cooperative relationship to each other at predetermined times.

7. In a box loom of the type in which pattern

mechanism automatically controls the shifting of the shuttles in the drop box, the combination of means for gripping a strand of filling running from the selvage of the fabric in the loom to an idle shuttle in the drop box, mechanism for operating said gripping means comprising an arm movable with the lay and a normally stationary cam cooperating with said arm to swing the latter, and means under the control of the pattern mechanism of the loom for shifting said cam automatically into and out of cooperative relationship to said arm.

8. In a box loom of the type in which pattern 85 mechanism automatically controls the shifting of the shuttles in the drop box, the combination of means for gripping a strand of filling running from the selvage of the fabric in the loom to an idle shuttle in the drop box, a cutting mechanism arranged to be operated by the motion of the lay for severing said strand at a point adjacent to the selvage of the cloth, and means under the control of the pattern mechanism of the loom for bringing said cutting mechanism into operation and throwing it out of operation again at predetermined times.

9. In a box loom of the type in which pattern 90 mechanism automatically controls the shifting of the shuttles in the drop box, the combination of means for gripping a strand of filling running from the selvage of the fabric in the loom to an 95 idle shuttle in the drop box, a cutting mechanism for severing said strand at a point adjacent to the selvage of the cloth, said cutting mechanism including relatively movable blades and means for utilizing the motion of the lay to operate them, 100 a latch mounted in cooperative relationship to said cutter to catch a part of the cutter mechanism when it is forced forwardly by the lay, and means under the control of the pattern mechanism of the loom for automatically controlling 115 said latch.

10. In a loom having pattern mechanism for controlling certain of the operations of the loom, the combination with a selvage cutter comprising a supporting frame, two relatively movable blades 120 mounted on said frame and adapted to operate closely beside the selvage at the fell of the goods, and power driven means for relatively moving said blades to operate the cutter, of additional means under the control of the pattern mechanism of the loom for bringing said cutter operating means into operation and throwing it out of operation again at predetermined times.

11. In a box loom of the type in which pattern 125 mechanism automatically controls the shifting 130 of the shuttles in the drop box, the combination of means mounted on the lay of the loom for gripping a strand of filling running from the selvage of the fabric in the loom to an idle shuttle in the drop box, mechanism for operating 135 said gripping means comprising a part movable with the lay and a normally stationary member cooperating with said part to move it relatively to the lay, means under the control of the pattern mechanism of the loom for shifting said 140 normally stationary member into and out of cooperative relationship to said part carried by the lay to bring said gripping means into action for a time immediately after a working shuttle has been retired at the drop box and to automatically render said gripping means inactive again after a brief interval of operation, and means for cutting the strand so gripped at a point adjacent to the selvage of the goods.

12. A thread holding apparatus for box looms 150

- comprising parts for gripping and holding a strand of filling, a blade cooperating with said parts to force a bight of filling between them, a bracket for supporting said blade and said parts, 5 a pivot on which said blade is mounted, and an arm connected with said blade to operate it, said arm being pivoted on said bracket and extending outwardly away from the bracket. 13. A thread holding apparatus for box looms 10 comprising parts for gripping and holding a strand of filling, a blade cooperating with said parts to force a bight of filling between them, a bracket for supporting said blade and said parts, a pivot on which said blade is mounted, an operating arm for said blade pivoted on said bracket and mounted to swing in a plane at approximately right angles to the plane of movement of the blade, and connections between said arm and said blade for causing the movement of the arm 15 to operate the blade. 14. In a loom having pattern mechanism for automatically controlling certain of its operations, the combination with a selvage cutter comprising two relatively movable blades arranged 20 to operate closely beside the selvage at the fell of the goods, and means arranged to be operated by the motion of the lay for relatively moving said blades to operate the cutter, of additional means under the control of said pattern mechanism of the loom for bringing said cutter operating means into operation and throwing it out of operation again at predetermined times. 15. In a box loom of the type in which pattern mechanism automatically controls the shifting 25 of the shuttles in the drop box, the combination of means mounted on the lay of the loom for gripping a strand of filling running from the selvage of the fabric in the loom to an idle shuttle in the drop box, power driven mechanism for operating said gripping means, and additional means under the control of the pattern mechanism of the loom for bringing said gripping means into operation and throwing it out of operation again at predetermined times. 45 16. In a box loom of the type in which pattern mechanism automatically controls the shifting of the shuttles in the drop box, the combination of means mounted on the lay of the loom for gripping a strand of filling running from the selvage of the fabric in the loom to an idle shuttle in the drop box, mechanism under the control of the pattern mechanism of the loom for operating said gripping means, means for definitely guiding said strand into position to be gripped by said gripping means, and means for severing the strands so gripped at a point closely adjacent to the selvage of the goods. 17. In a box loom of the type in which pattern mechanism automatically controls the shifting of the shuttle in the drop box, the combination of means mounted on the lay of the loom for gripping a strand of filling running from the selvage of the fabric in the loom to an idle shuttle in the drop box, mechanism for operating said gripping means, means for severing a strand of filling so gripped at a point adjacent to the selvage of the goods, means for normally holding both said clamping means and said severing means in an active condition, and connections for causing the pattern mechanism of the loom to bring both said severing and gripping means into operation temporarily when the pattern mechanism retires a working shuttle at the drop box. 18. In a box loom of the type in which pattern mechanism automatically controls the shifting of the shuttles in the drop box, the combination of means for gripping a strand of filling running from the selvage of the fabric in the loom to an idle shuttle in the drop box, means for definitely guiding said strand into position to be gripped by said gripping means, cutting mechanism for severing said strand at a point closely adjacent to the selvage of the cloth, power driven means for operating said cutter mechanism, and means under the control of the pattern mechanism of the loom for bringing said operating mechanism into operation and throwing it out of operation again at predetermined times. 50 55 60 65 70 75 80 85 90 95 100 105 110 115 120 125 130 135 140 145 150
